UNITED STATES PATENT OFFICE.

CLARENCE ELMER CHAMBERS, OF SAN JACINTO, CALIFORNIA.

STRAW-BURNING TRACTION-ENGINE BOILER.

SPECIFICATION forming part of Letters Patent No. 723,241, dated March 24, 1903.

Application filed August 12, 1901. Serial No. 71,833. (No model.)

To all whom it may concern:

Be it known that I, CLARENCE ELMER CHAMBERS, a citizen of the United States, residing at San Jacinto, in the county of Riverside and State of California, have invented a new and useful Straw-Burning Traction-Engine Boiler, of which the following is a specification.

This invention is particularly designed for a steam-boiler to be used on a traction-engine adapted for burning straw. It is also adapted, however, for burning other kinds of fuel and is an economical boiler for stationary engines and also for locomotive-boilers.

One of the objects of this invention is to provide a steam-boiler of great capacity which is capable of ascending and descending steep grades without exposing the crown-sheet to the steam.

Another object is to provide a very narrow boiler of great strength and large capacity, so that it can be carried on wheels having a very narrow tread between them.

Another object in view is to provide great strength and also to provide against lodgment of sediment on any part of the boiler subject to the action of the flame, thereby to prevent any burning out of the boiler.

The accompanying drawings illustrate my invention.

In the drawings I have omitted the stay-rods and braces, and it is to be understood that in constructing the boiler the necessary braces and stay-rods will be employed.

Figure I is a longitudinal mid-section of a boiler embodying my invention. Fig. II is a front elevation of the boiler. Figs. III, IV, and V are sections, respectively, on lines III, IV, and V, respectively, Fig. I, looking to the left. Fig. VI is an elevation on line VI, Fig. I, looking to the right.

1 2 3 indicate in a general way a combined boiler-shell, steam-dome, and water-leg.

4 indicates a fire-box located within the water-leg and below the steam-dome and having between its ends an upward extension 5 and a flue-sheet 6, forming the front wall of said upward extension.

7 indicates a smoke-box at the front end of the boiler. Said smoke-box is provided with a suitable smoke-outlet 8 into a smoke-stack 9, leading therefrom.

10 indicates the tubes extending through the body of the boiler between the flue-sheet 6 of the fire-box and the flue-sheet 11 of the smoke-box.

12 indicates the upper front sheet of the fire-box, and the same is bent in a semicylindrical form and extends between the lower water-space of the boiler and the front of the fire-box and is connected at the rear with the flue-sheet 6 and at front and sides with the inside wall 13 of the water-leg. Said front sheet of the fire-box slopes forward and downward beneath the tubes 10 to the wall of the water-leg 3.

a indicates the boiler-shell, the front portion b of which is cylindrical, and said shell has at its rear end an upward extension c to form the steam-dome above the tubes and the fire-box. The transverse diameter of the upward extension c of the boiler-shell is approximately the same as the diameter of the cylindrical portion b of said boiler-shell, and the water-leg 3 is preferably of no greater diameter from side to side than the greatest diameter of the shell. The upward extension c of the boiler is above the level of the cylindrical portion b, and the forward extension of the water-leg is below said portion. The upward extension 5 of the fire-box is between the body of the boiler and the water-leg of the boiler.

By constructing the parts in this manner a thin body of water is exposed to the action of the heat at the sides and on top of the leg extension and also at the sides of the fire-box extension, thereby heating it very quickly and causing a very rapid circulation of the water between the leg and the main portion of the boiler. The extension of the leg forward permits of the insertion of a sufficient quantity of straw to generate the desired amount of steam and also causes the flames to be drawn longitudinally through the leg, thereby causing a complete combustion of the straw, and by locating the crown-sheet 12 at the forward end of the fire-box and inclining it upward to the rear the blaze from the forward extension of the fire-box strikes it and is checked before passing up into the vertical extension 5. This lessens the liability of carrying any unconsumed straw or fuel up into and through the water-tubes, and it also causes the water resting on

the crown to be heated to the greatest possible extent, thereby helping to increase the circulation of the water and the generation of steam. The vertical distance between the bottom of the fire-box and the top of the boiler extension greatly exceeds the transverse width of the boiler, whereby a tall and narrow boiler is produced, which is very desirable for the form of traction or portable engines to which my improved boiler is more particularly applicable, and by reducing the water area at each end and increasing it vertically at the center the inclination of the boiler in vertical plane will not be so apt to expose any portion of the tubes or crown-sheet, thereby adapting the engine for use over a rough or hilly country. The forward crown-sheet 12 of the fire-box slopes forward and downward to the water-leg 3 in order that any sediment which may fall thereon may slide down therefrom into the water-leg.

14 indicates a blow-off cock which may be located at any desirable point and is preferably in such a position as to readily blow off the sediment which may fall on the crown-sheet 12. The crown-sheet 15 of the upward extension 5 of the fire-box is located below very shallow water, for in practice the water-line of the boiler will come above the level of the cylindrical portion *b* of the boiler-body. In Fig. IV it is seen that the semicylindrical crown-sheet 15 has an internal convexity extending into the water-space of the boiler, so that when the blow-off cock 14 is open the flow of water carried from above downward to the cock 14 will have a tendency to wash the sediment, if any, from the crown-sheet. The lower semicylindrical crown-sheet 12 is inwardly concave for a like purpose, so that when the blow-off cock 14 is open the flow of the water in the boiler down the sheet 12 will carry the sediment, if any, down into the water-leg and to the blow-off cock.

16 indicates the furnace-door, and 17 the grate-bars of the usual type. The fire-box is greatly elongated between the furnace-door 16 and the upward extension 5 and is surrounded at the top and sides of such elongated portion with the water-leg 3, so that the fire-box is approximately inclosed in said water-leg.

18 indicates the steam-pipe leading from the steam-dome. This pipe may be located at any suitable place.

55 The steaming capacity of the boiler is made very great by the feature of construction shown, in which the fire-box is so extended and so inclosed by the water-chamber of the boiler, and the heating-surface is greatly increased by this construction. Furthermore, a large body of dry steam is provided for by the upward extension of the fire-box to nearly above the water-level of the boiler.

65 It is to be understood that the water-level may be varied within the judgment of the engineer, and it will also be understood that

the correct practice is to allow the flues and fire-box to be always submerged in the water.

In ascending or descending practical grades 70 the surfaces with which the fire comes into contact will remain below the water-level 19, the steam-dome being only over a central portion of the boiler and the body of water being sufficient to cover the parts with which it 75 comes in contact.

The smoke-box 7 is surrounded at the sides by the water-space 20 of the boiler, so that the heat which passes through the tubes 10 into the smoke-box will be largely utilized 80 in producing steam. The upward extension 2 slopes rearwardly up from the cylindrical body *b*, so that the steam readily passes up into the steam-dome *c*. The greatest steam-space is immediately above the portion of the 85 fire-box where the greatest heat is applied, so that there is as little friction and loss of power possible in the movement of the steam from the place of its most rapid generation to the steam-space *c*—that is to say, said 90 steam-space *c* is immediately above an enlargement of the fire-box and above that portion of the tubes which receives the hottest flame.

The fire-box comprises the trunk *d*, the upward extension 5, and the forward extension *e*, all within the water-space of the boiler. The trunk *d* is preferably of considerable length for the purpose of economically burning straw.

In practice the fuel will be fed into the furnace in the ordinary way, and the heat is taken up by the contents of the main shell and the water-legs of the boiler which approximately surround the fire-box and the smoke- 105 box.

I believe that a boiler provided with a fire-box comprising a trunk and a forward extension and an upward extension intermediate the fire-box trunk and the forward extension 110 and a water-leg around the sides and top of the trunk and at the sides of the extension and above the front of the extension is novel. I also consider that a boiler having a fire-box furnished with a semicylindrical crown-sheet 115 extending rearward from above the tubes of the boiler and also provided with a semicylindrical crown-sheet extending in a forward direction underneath the rear portion of said tubes is a novelty in the construction of boilers. The fire-box trunk, with the forward extension and the upwardly-extending chamber thereof, constitutes a fire-box which is especially adapted for the burning of straw or similar material and allows of perfect combustion, and the water-legs therearound are adapted for the absorption of the heat generated from the combustion of such materials. The arrangement of the semicylindrical crown-sheet extending rearwardly from 120 above the tubes of the boiler allows any sediment which may collect thereon to be readily drawn downwardly along the sides of the crown-sheet when the blow-off valve is opened, 130

and the semicylindrical crown-sheet extending forwardly underneath the rear portion of said tubes, which is over the forward extension of the fire-box, affords a channel leading the 5 sediment collected upon such crown-sheet into the path of the outflowing water when the blow-off valve is opened.

By providing my boiler with water spaces or legs in the manner disclosed in front of and 10 around the fire-box, that portion which is around the trunk of the fire-box being at a lower level than that which is in front of the upward extension of the fire-box, I provide a boiler which, having a steam-dome intermediate 15 its length and above the fire-box, has at all times a covering of water over the fire-box (when a sufficient supply of water is in the boiler) whenever the boiler is ascending or descending any reasonable grade, thereby 20 preventing the danger or liability of burning the crown-sheet. This feature I do not believe to have been used in a traction-engine boiler before my invention.

What I claim, and desire to secure by Letters Patent of the United States, is—

1. A boiler provided with an elongated water-leg having a fire-box therein, said box being provided with a vertical extension intermediate its ends, and tubes or flues leading 30 from said extension through the boiler.

2. A boiler provided with an elongated water-leg and having a fire-box therein, said box being provided with a vertical extension intermediate its ends, the top of the rear end of 35 the box being substantially horizontal and convex and the top of the forward portion being inclined and concave.

3. A boiler provided with an elongated water-leg and having a fire-box therein, said box 40 being provided with a vertical extension intermediate its ends, the boiler being provided with a blow-off cock substantially midway of its width and on a line with the bottom of the water-leg, the top of the rear portion of 45 the fire-box being convex and the forward end being concave and inclined toward the blow-off cock.

4. A boiler provided at its rear end with a 50 vertical extension and a rearwardly-projecting water-leg, a fire-box in the water-leg, the top of which is provided with a vertical ex-

tension intermediate its ends, the top of the fire-box extension terminating at a distance below the top of the boiler extension, and the sides and top of the fire-box lying adjacent 55 to the sides and top of the water-leg and the sides of the vertical extension lying adjacent to the sides of the boiler, whereby a rapid circulation of water and generation of steam is effected.

5. A boiler provided with a cylindrical forward end and a vertical extension and an elongated water-leg at the rear end, the vertical extension being above and the water-leg being below the level of the main portion of 65 the boiler; a smoke-box in the forward end, a fire-box within the water-leg, the walls of which lie adjacent to the walls of the water-leg and the top provided with a vertical extension intermediate its ends, the top of said 70 extension being at a distance below the top of the boiler extension, and fire-tubes from the top of the fire-box extension to the smoke-box, the flues occupying the main part of the tubular portion of the boiler, whereby the 75 water-space at the center is greater than at either end.

6. A boiler provided with a cylindrical forward end and a parallel-sided vertical extension and an elongated water-leg at the rear 80 end, the vertical extension being above and the water-leg below the level of the main portion of the boiler, the width of the boiler, the extension and the water-leg being the same and the height of the boiler through the 85 rear end of the vertical extension and the forward portion of the water-leg greatly exceeding the width of the boiler, and a fire-box in the water-leg, the top of which is provided with a vertical extension intermediate its 90 ends, the top of the fire-box extension terminating at a distance below the top of the vertical boiler extension.

In testimony whereof I have signed my name to this specification, in the presence of 95 two subscribing witnesses, at San Jacinto, in the county of Riverside and State of California, this 1st day of August, 1901.
